UNITED STATES PATENT OFFICE.

JACOB L. BROSCHART, OF TRENTON, MISSOURI, AND EDWARD F. BERNEKING, OF ATCHISON, KANSAS.

COMBINED THREADER, REAMER, AND WRENCH.

1,161,377.

Specification of Letters Patent. Patented Nov. 23, 1915.

Application filed April 20, 1915. Serial No. 22,681.

To all whom it may concern:

Be it known that we, JACOB L. BROSCHART and EDWARD F. BERNEKING, citizens of the United States, residing at 1103 Harris 5 avenue, Trenton, in the county of Grundy and State of Missouri, and Atchison, in the county of Atchison and State of Kansas, respectively, have invented a new and useful Combined Threader, Reamer, and 10 Wrench; and we do hereby declare the following to be a full, clear, and exact description of the invention, such as will enable others skilled in the art to which it app pertains to make and use the same.

15 This invention relates to an improved combined threader, reamer and wrench, in other words an object of the invention is to provide an improved stock for holding and operating either an internal or external 20 threading die or a reamer, or an external threading die and reamer combined, or a wrench die.

Another object of the invention is to provide a simple, inexpensive, efficient and practical device of this nature, having improved features of construction, and also provides a device of this nature, which may be used or employed in a limited space.

Another object of the invention is the provision of means whereby the device may be used for cutting quite a long thread on a pipe.

In practical fields the details of construction may necessitate alterations, falling 35 within the scope of what is claimed.

The invention comprises further features and combination of parts, as hereinafter set forth, shown in the drawings and claimed.

In the drawings:—Figure 1 is a view in 40 perspective of the improved stock. Fig. 2 is a perspective view showing the other face of the stock. Fig. 3 is a longitudinal sectional view showing a die and a reamer held in the stock for reaming and cutting threads 45 at the same time. Fig. 4 is an end view of a handle of the stock showing the groove in the end thereof for receiving the rib of the cap of the stem of the pawl. Fig. 5 is a face view of the cap or head of the stem of the ratchet. Fig. 6 is a sectional view on 50 line 6—6 of Fig. 3, showing the reamer and the external pipe threading means. Fig. 7 is a plan view of the stock showing an internal pipe tap or threading means. Fig. 8 55 is a sectional view on line 8—8 of Fig. 7.

Fig. 9 is a sectional view through the stock showing external threading means, whereby a long thread may be supplied on a pipe. Fig. 10 is a detail perspective view of the reamer. Fig. 11 is a view showing the stock 60 holding a wrench die, for backing off or unscrewing a nut, and the opening in this die may be either square or other polygonal shape.

Referring more especially to the drawings, 1 designates the stock, which comprises an annular band 2 having a hollow shank 3, in which the tubular stock handle 4 is threaded as shown at 5. One edge portion of this annular band is provided with an 65 inturned annular flange 6, whereas the inner circumference of the band adjacent the other edge portion of the band is provided with internal threads 7. In all the figures excepting Fig. 9 an annular back plate 8 is provided, the edge portion of which is provided with a rabbet 9 to receive the inturned flange 6, and adjacent this back plate any 70 form of die 10 may be arranged, either a die having thread cutters as shown at 11 80 in Figs. 2, 3, 6 and 9, or either a die as shown at 10^a in Fig. 7 having a square opening 10^b for backing off nuts. This opening 10^b may be any other shape than that shown. Threaded at 12 in the back plate is a screw 85 13 having a conical head 14 to engage a suitable abutment merely indicated at 15 for pivotally supporting the stock while the same is being used to perform its work. This screw is supplied with a reduced portion 90 16, on which a suitable reamer or the like 17 is arranged. This reamer is employed for reaming, cutting or removing the bur upon the inner circumference of a pipe or the like. This reaming or removing of 95 the bur may be accomplished independently, or at the same time with the cutting of the thread on the exterior of the pipe. The end face of the reamer 17 is constructed with a rib 18, which engages a correspondingly shaped recess or groove 19 upon the inner face of the back plate, so that the reamer and the back plate will rotate as one body. Regardless of the form of guide to be used, it is to be understood, however, that each 100 die is to be constructed with an aperture 20, whereas the back plate is designed to have an aperture 21, to receive a thumb pin 22, which in turn enters the aperture 20, in order to connect the die to the back plate. 105 110

The die is connected to the back or die plate, only when it is desired to ream or remove the bur, and cutting exterior threads at the same time, and also when desiring to cut the 5 interior and external threads on a pipe at the same time, as disclosed clearly in Figs. 7 and 8. When it is desired to ream the inner surface of the pipe without cutting external threads, the thumb pin 22 remains in 10 said registering apertures, so that the back plate and the die will rotate together, but in this case the opening in the die is circular. When it is desired to cut external threads 15 without reaming the thumb pin is removed, so that the back plate and the reamer will remain idle, while the die will be rotated intermittently and independently thereof. In this case the reamer acts as a guide, in order that a uniform thread may be cut externally 20 on the pipe.

The reamer as shown in Fig. 10 is provided with the usual cutting edges 23, whereas in Figs. 7 and 8 an internal thread cutting die 24 having thread cutters 25 is arranged or applied to the reduced portion 16 of the screw 13, and in which case this die is provided with a rib 26 similar to the rib 18 to be received in the groove 19 of the back or die plate, so that the guide 24 will rotate 25 with the back plate, and to cut internal threads the thumb pin remains in the apertures 20 and 21. However, in this case when it is desired to cut internal threads without cutting external threads the opening of the 30 die 10 is circular. As shown in Fig. 9 a pipe may be provided with a thread of considerable length. In this instance the back plate may be removed, and the die 10 allowed to engage the inturned flange 6 of 35 the band 2 of the stock, or instead of the back plate 8 a ring 28 having a rabbet 29 to engage the flange 6 may be employed, thereby permitting the die 10 as shown in Fig. 9 to rotate against the ring. In this 40 manner it will be observed that a pipe, when it is to be supplied with external threads of considerable length, may extend entirely through the die and the band as shown in Fig. 9. Every form of die 10, whether used 45 for backing off nuts or cutting external threads are designed to have teeth preferably of the type shown at 30, and mounted in the hollow shank 3 is a ratchet dog 31 having a stem 32 threaded to the dog as 50 shown at 33. Interposed between the dog and a collar 34 on the stem adjacent one end of the handle 4, is a coil spring 35, the action of which holds the nose 36 of the ratchet dog in engagement with the teeth 30 55 of the die member 10, and in such wise, that when the stock handle 4 is thrown in one direction, the die will rotate with the stock band, so that the cutters 11 or the reamer will perform their work, and when the handle 4 is moved in the opposite direction, the

nose 36 is so beveled as shown at 37 as to slip over the teeth. In this manner an intermittent motion is imparted to the die and the reamer. Threaded upon the stock handle as at 38 is a sleeve 39, the end portion of 60 which is provided with a transverse groove 40. Threaded or otherwise secured upon the stem 32 as shown at 41 is a cap 42 having a reduced portion 43 telescoping into one end of the sleeve 39. Formed upon one face of 65 the cap 42 upon opposite sides of the reduced portion 43 are lugs 44, which enter the grooves 40 of the sleeve 39, to prevent annular displacement of the ratchet dog 31, when the same is in action. By grasping the 70 cap 42 and pulling outwardly thereon the nose of the ratchet dog may be disengaged from the teeth 30 of the die, so that the stock handle 4 may be moved to another position more conveniently, when such is necessary. 75 Referring to Fig. 3 it is to be noted that the ratchet dog may be reversed in position to that shown, by pulling outwardly upon the cap, and imparting a half revolution to the same, and allowing the lug 44 to engage the 80 groove 40, subsequently to permitting the spring 35 to restore the nose 36 of the dog in engagement with the teeth 30 of the die, in order that an intermittent motion may be 85 imparted to the die in the direction opposite to that previously set forth. To hold the die 10 or similar member in the band a ring 50 is connected to the threads 7 of the band, and this ring is provided with openings 51 to receive a spanner-wrench, where- 90 by the ring may be screwed in place. 95

The invention having been set forth, what is claimed as new and useful is:—

1. A stock and die comprising a band having a stock handle, a back plate loosely movable in said band and provided with a concentrically arranged cutter, an annular die carried by the back plate loosely movable in said band and having outer circumferential teeth, and means in said handle to coöperate with the teeth for imparting intermittent motion to the die. 105

2. A stock and die comprising a band having a stock handle, a back plate loosely movable in said band and provided with a concentrically arranged cutter, an annular die loosely movable in said band and having outer circumferential teeth, and means in said handle to coöperate with the teeth for imparting intermittent motion to the die, 110 and means for detachably connecting the annular die and the back plate. 115

3. A die stock for holding reamers, thread cutting and wrench dies, comprising a band having a stock handle and provided with an inturned flange on one edge, a backing member engaging said flange and provided with means to hold a reaming member, an annular die engaging said backing member and provided with exterior circumferential 120 125 130

ratchet teeth, means for holding the annular die in the band adjacent the backing member, a thumb pin passing through the backing member and the annular die for detachably connecting the same, and ratchet means in the stock handle to coöperate with the ratchet teeth of the die for imparting intermittent motion to the die.

In testimony whereof we have signed our

names to this specification in the presence 10
of subscribing witnesses.
